INVENTOR:

Albert Abbe Griswold

By Chas. H. Luther

ATTORNEY:

UNITED STATES PATENT OFFICE.

ALBERT ABBE GRISWOLD, OF PROVIDENCE, RHODE ISLAND, ASSIGNOR OF ONE-HALF TO
JOHN FRANCIS CHEVALIER, OF BROOKLINE, MASSACHUSETTS.

WIRE-NAIL SHINGLE-CLAMP.

1,320,136.

Specification of Letters Patent.

Patented Oct. 28, 1919.

Application filed April 25, 1918. Serial No. 230,790.

To all whom it may concern:

Be it known that I, ALBERT ABBE GRISWOLD, a citizen of the United States, residing at Providence, in the county of Providence and State of Rhode Island, have invented a new and useful Improvement in Wire-Nail Shingle-Clamps, of which the following is a specification.

My invention has reference to an improvement in means for securing shingles to roofs and the like, and more particularly to an improved combined wire-nail and shingle clamp for fastening down the otherwise free end of flexible shingles, in shingling a roof or the like, with flexible shingles.

In the construction of roofs and the like on which flexible shingles are used, it is necessary to hold down the free ends of the shingles so as to prevent bending or curling up of the shingles, thereby giving an unsightly appearance and allowing rain, snow or sleet to beat up under the shingles.

The object of my invention is to improve the construction of a combined wire-nail and shingle clamp whereby in driving the nail, the end of a flexible shingle is simultaneously clamped down in place and the upper end of a shingle previously laid is nailed down in one operation.

My invention consists in the peculiar and novel construction of a wire-nail shingle clamp formed integral of wire and so constructed as to clamp down a bent under flap on the outer end of a flexible shingle, and to nail down the upper end of a shingle previously laid, in driving the nail portion of the clamp, said wire-nail shingle clamp having details of construction, as will be more fully set forth hereinafter and claimed.

Figure 1, is a face view of a portion of a flexible shingled roof showing the flap on one of the shingles clamped down and the upper end of a shingle previously laid, nailed down, by one of my improved wire-nail shingle clamps.

Fig. 2 is an enlarged face view of my improved wire-nail shingle clamp showing the same in position for clamping down the bent under flap of a flexible shingle.

Fig. 3 is an enlarged side view of the wire-nail shingle clamp showing the same

clamping down the bent under flap of a flexible shingle, and

Fig. 4 is an enlarged perspective view of the wire-nail shingle clamp. 55

In the drawing 5 indicates the boarding of a roof, 6.6 flexible shingles, and 7.7 my improved wire-nail shingle clamps. The roof boarding 5 may also represent the boarding on the outer walls of a building. 60

The flexible shingles 6.6 may be constructed of paper, tar and gravel or other flexible composition or fibrous material. Each shingle 6 has its outer end or corner bent under and formed into a flap 8, as shown in Figs. 65 1, 2 and 3.

My wire-nail shingle clamp 7 is constructed to have a straight body portion 9, on one end of which is a downwardly bent wire-nail member 10 having a pointed end 70 11 and on the other end of the body portion 9 a clamping member 12 bent sidewise from the body portion 9, all formed integral of wire, as shown in Fig. 4.

In using my improved wire-nail shingle 75 clamp in shingling a roof or the like with flexible shingles 6.6, the shingles 6.6 are laid diagonally, each shingle in a course being first laid with the underside outward and the flap 8 pointing upward. A wire-nail 80 shingle clamp 7 is now placed over the flap 8 on the shingle in a position to bring the clamping member 12 centrally across the flap 8 adjacent the bend in the flap and with the wire-nail pointing downward above the 85 flap 8, and on to the upper end of a shingle previously laid. The wire-nail member 10 is then driven through the upper end of the previously laid shingle in the lower course and into the roof boards 5.5, thereby clamping 90 down the flap 8 on the shingle and nailing down the upper end of the previously laid shingle. The shingle being laid is then bent up over the wire-nail shingle clamp, as shown in heavy dotted lines in Fig. 1 and 95 laid flat on the roof, face outward, and the shingling continued, the shingles being laid in each course as described.

By the use of my improved wire-nail shingle clamp the flap 8 on a shingle is clamped 100 down and the upper end of a previously laid shingle is nailed down in one operation,

therefore, only one wire-nail shingle clamp and only one operation is required for clamping down the flap on the outer end of a shingle and nailing a shingle in place.

5 I do not wish to confine myself to the construction shown, as the shape of the wire-nail shingle clamp could be modified and the material used varied, within the scope of the appended claims.

10 Having thus described my invention, I claim as new:

The combination with the boarding of a building of a flexible shingle having a turned under flap, a wire-nail shingle clamp 15 having a straight body portion, on one end

of which is a downwardly bent wire-nail member having a pointed end adapted to be driven into the boarding, and on the other end of the body portion a clamping member bent sidewise and at right angles to the wire-nail member and adapted to lie flat on the turned under flap on the flexible shingle, whereby the turned under flap of the shingle is clamped in place on the boarding and the shingle clamp is concealed and protected by the shingle when said nail member is driven to position.

In testimony whereof I have signed my name to this specification.

ALBERT ABBE GRISWOLD.
